UNITED STATES PATENT OFFICE

FRED P. BIEDERWOLF, OF MONTICELLO, INDIANA

SMOKE CONTROL DEVICE

Application filed July 19, 1929. Serial No. 379,367.

This invention relates to means for eliminating smoke from chimneys, stacks and the like, and particularly to means for automatically regulating the amount of air passing over the top of a fire within a fire-box.

In firing furnaces, particularly in residences where the fire-box is charged intermittently and an attendant is not regularly stationed at the furnace, the common practice is to shovel in a quantity of coal sufficient to last over a considerable interval of time so that the actual periods of firing may be spread apart as far as may be possible in maintaining a fire, with the result that, when the new supply of coal is put in the fire-box, the bed of live coals is completely covered over with a layer of coal of sufficient depth to effectually cut off air passages therethrough until the fire below may burn holes to let air entering from below the fire bed to pass up through and supply the necessary amount of oxygen required for combustion.

In other words, the normal draft of air from below the fire and on into the stack is temporarily checked until the fire can eat up through the green coal. While this process of readjustment is taking place, large quantities of smoke and gas are passing out the stack. Sufficient air is not supplied over the top of the coal to support combustion of the gaseous products being driven off from the coal by the fire below.

It is the primary purpose of my invention to provide means whereby air may automatically be supplied above the fire bed at each charging of the fire-box with a supply of green coal and be automatically reduced and cut off as the coal burns and restores the natural draft up through the coal, all without thought or action upon the part of the fireman.

Further objects reside in providing a structure for the purpose above stated that may readily be applied to existing fire-box doors without material change; in providing a structure requiring no further attention after installation; and that may be produced and installed at a very low cost.

I accomplish these and other objects as will become apparent in the following de-

scription of the device as shown in the accompanying drawings in which—

Fig. 1 is a front elevation of a fire-box door with my invention applied thereto;

Fig. 2, a vertical section on the line 2—2 in Fig. 1;

Fig. 3, a horizontal section on the line 3—3 in Fig. 1; and

Fig. 4, a rear elevation of the door as shown in Fig. 1.

Like characters of reference indicate like parts throughout the several views in the drawings.

The door 10 here shown is the usual door on a furnace (not shown) through which coal is supplied to replenish the fire, the door 10, being therefore, the one above the fire bed. I form a frame 11, preferably of angle iron and mount it in the door in place of the usual slide damper (not shown) employed in such doors. The frame 11 is employed to support a number of slats here shown as three in number consisting of the slats 12, 13, and 14 rockably secured in the frame by the pins 15 and capable of being revolved thereabout on parallel horizontal axes.

Each of the slats 12, 13, and 14 are the same in shape and have an S-shape in cross section (Fig. 2). The pins 15 project from the ends of the slats on an axis slightly above the centers of gravity of the slats so that each slat normally tends to rock by its pins 15 in the frame to hang vertically disposed, as shown in Fig. 2, where the rearwardly projecting upper lip of one slat will extend over and contact the forward face of the forwardly projecting lower lip of the next above slat to form a seal therebetween. Lips 16 and 17 are provided in the frame as stops for the slats 12 and 14.

Immediately back of the front of the door to which the frame 11 is attached, is the usual baffle plate 18 with an air space therebetween. The plate 18 is provided with a plurality of holes 19 therethrough preferably increasing in size from top to bottom whereby most of the air passing through the plate 18 will pass through the lower holes 19 nearer the bed of fire therebehind.

Normally, the slats 12, 13, and 14 will hang

in the closed position as shown by the solid lines in Fig. 2, when the fire behind the door is burning freely with the lower draft door (not shown) open to allow air to pass up through the fire bed. Now when the bed is covered with a fresh supply of coal, the normal draft through the bed is checked, so that a slight vacuum in the fire-box above the coal is produced and will cause air to be pulled against the slats 12, 13 and 14 with the result that the slats, being nearly balanced on the pins 15 (being out of balance just enough to insure closure under normal fire conditions), will be rocked by the air pressing against the slightly longer sections below the pins 15 to cause the slats to be rocked open as indicated by the dotted lines to let a current of air pass thereover against the plate 18 and be diffused through the holes 19 on over and above the fire bed.

As a further aid to diffusion of the incoming air, the lower edges of the slats, Fig. 1, may be serrated, by having teeth 20 formed therealong, normally covered by the upper lip of the slat therebelow.

As soon as air again starts coming through the fire bed the partial vacuum thereabove is reduced so that the slats 12, 13, and 14 may again drop to their normal closing positions, and the excess air theretofore entering to support combustion above the coal is shut off and the normal draft functions as before.

I claim:

1. The combination of a fire door having an opening therethrough, of a plurality of slats, S-shaped in cross-section and pivotally mounted on horizontal axes, said axes being slightly above the centers of gravity of the respective slats, and being so arranged that each slat contacts at one edge with an adjacent slat by the action of gravity to close said opening, said slats being mounted so that each may swing independently of the others to open position under the influence of air pressure on the outer face thereof, and each having a serrated edge overlapped by an adjacent part when the slats are in closed position.

2. The combination of a fire door having an opening therethrough, of a plurality of slats, S-shaped in cross-section and pivotally mounted on horizontal axes, said axes being slightly above the centers of gravity of the respective slats, and being so arranged that each slat contacts at one edge with an adjacent slat by the action of gravity to close said opening, said slats being mounted so that each may swing independently of the others to open position under the influence of air pressure on the outer face thereof, and each having a serrated edge overlapped by an adjacent part when the slats are in closed position, and a baffle plate carried by the door spaced behind the slats having a plurality of horizontal

rows of holes therethrough, which holes increase in size from the top row to the bottom row.

In testimony whereof I affix my signature.

FRED P. BIEDERWOLF.
